UNITED STATES PATENT OFFICE.

LESTER M. TAYLOR, OF WILKINSBURG, PENNSYLVANIA, ASSIGNOR TO WESTINGHOUSE ELECTRIC AND MANUFACTURING COMPANY, A CORPORATION OF PENNSYLVANIA.

STARTING MECHANISM FOR GAS ENGINES.

Application filed April 29, 1915. Serial No. 24,750.

To all whom it may concern:

Be it known that I, LESTER M. TAYLOR, a citizen of the United States, and a resident of Wilkinsburg, in the county of Allegheny and State of Pennsylvania, have invented a new and useful Improvement in Starting Mechanisms for Gas Engines, of which the following is a specification.

My invention relates to starting mechanisms for gas engines, and it has particular reference to such mechanisms as embody screw-threaded shafts for automatically effecting the operative connection of starting motors to the shafts of internal combustion engines.

One object of my invention is to provide a simple means for preventing the oscillation of a spring which connects two relatively rotatable shafts incident to variations in load connected to one of said shafts.

A second object of my invention is to provide a simple and efficient means for firmly securing the respective ends of a connecting spring to two relatively rotatable shafts.

A further object of my invention is to provide a simple means for frictionally engaging a pinion at the end of its path of longitudinal movement on a screw-threaded shaft.

In the operation of starting mechanisms of the same general character as that of my invention, it has been found that the variations in torque required to rotate an engine shaft as the engine approaches or recedes from each of its several compression points, causes a spring, which resiliently connects the screw-threaded shaft to the motor, to be alternately contracted and expanded. The variations in load set up oscillations of the spring which have the effect of tending to periodically effect the disconnection of the pinion from the fly wheel.

It has also been found, in practice, that it is difficult to so secure the connecting spring to the relatively rotatable shafts which it connects that the force to which it is subjected upon the back firing of the engine will not cause the spring to be disconnected from the shafts. Another disadvantage incident to the use of some of the ar-

rangements heretofore proposed is that the pinion, which is actuated longitudinally on a screw-threaded shaft by relative rotation of the parts, is actuated outwardly with such force that it strikes, with considerable impact, the collar which limits its outward movement.

I provide a split sleeve which is interposed between the helical spring and the relatively rotatable shafts which it connects. When the spring is contracted by relative movement of the shafts, it first engages the resilient split sleeve, and further relative movements of the several convolutions of the spring are opposed by their frictional engagement with the sleeve. The resilient force of the sleeve is also added to that of the spring to resist relative movement of the shafts.

When the spring is contracted to such a degree that the split sleeve is caused to firmly grip the adjacent ends of the relatively rotatable shafts, relative movement between them is prevented or materially limited because of their frictional connection by the resilient sleeve. This construction operates to prevent or damp out the oscillation of these parts which are due to the variations in load above described. The gripping action of the sleeve operates, also, to relieve the spring of some of the load, as the ends of the shafts are, to some extent, directly connected. Concentration of the load at the terminal loops or anchoring ears of the spring is thereby prevented.

I provide also a spring which has terminal loops of such form that the spring cannot be disconnected from the shafts by back firing of the engine and which afford a convenient means for firmly securing the respective ends of the spring to the shafts. A resilient washer or buffer spring frictionally engages the pinion during a portion of its path of movement upon the screw-threaded shaft to exert a wedging action of the pinion with respect to the screw threads at the outer end of the screw-threaded shaft. The wedging action tends to prevent the disconnection of the pinion from the fly wheel when the engine recedes from its compression points.

The details of my invention will be described in connection with the accompanying drawings, in which Fig. 1 is a side view, partially in elevation and partially in section, of a starting mechanism constructed in accordance with my invention, part of the motor being broken away. Fig. 2 is a view, in transverse section, of the mechanism of Fig. 1. Fig. 3 is an end view of the split sleeve. Fig. 4 is an end view of a modification. Fig. 5 is a view, in longitudinal section, of the mechanism of Fig. 4.

Referring particularly to Figs. 1, 2 and 3, the plane of an engine fly wheel 1 is indicated by dot and dash lines in Fig. 1. A starting motor 2, which may be, for example, an electric motor, may be secured to the frame of an automobile or other motor vehicle in any suitable manner. The motor armature shaft 3 is provided with a pinion 4 which meshes with a gear wheel 5 on a short countershaft 6. A shaft 7 is mounted in axial alinement with the shaft 6 and is rotatably connected thereto by means of a reduced portion 8 which projects into a longitudinally extending bore 9 in the shaft 6.

The shafts 6 and 7 are resiliently connected by a helical spring 10 which surrounds their adjacent ends. The inner end of the spring 10 is bent to form a loop 11 which projects into a recess 12 that is formed in the gear wheel 5. The loop portion 11 is connected to the shaft 6 by means of a stud 13 which projects into the recess 12. The end portion 14 of the spring 10 extends adjacent to the outer face of the gear wheel 5 and substantially plane to its surface. The opposite end portion of the spring comprises a plurality of loops 15 and 16 which respectively engage a bolt 17 and a stud 18. The loop portions 15 and 16 form a terminal portion of substantially S-shape.

A cylindrical split sleeve 19 of resilient material, an end view of which is shown in Fig. 3, surrounds the adjacent end portions of the shafts 6 and 7 and is interposed between the shafts and the spring 10. The internal diameter of the split sleeve is slightly greater than the diameters of the shafts 6 and 7, so that, normally, the shafts are not engaged by the sleeve. When the internal diameter of the spring 10 is decreased, the sleeve 19 is caused to firmly engage the shafts 6 and 7 to prevent their relative movement.

The provision of the sleeve member 19 insures, also, that convolutions of the spring are not drawn into the space between the ends of the shafts 6 and 7 in case of relative axial movement of the shafts and the contraction of the spring. Such occurrences have caused the failure of many

springs in the operation of devices of this character.

The shaft 7 is provided with a screw-threaded portion 20 upon which is mounted a weighted pinion 21 for longitudinal movement thereon into and out of operative engagement with the fly wheel 1. The shaft 8 is provided with a collar member 22 at the outer extremity of the screw-threaded portion 20, adjacent to which is mounted a resilient washer or buffer spring 23 which serves not only to prevent the wedging action between the screw-threads and the collar member 22, but to receive the impact of the pinion 21 as it is forcibly actuated longitudinally on the shaft.

Normally, the various parts are in their respective illustrated positions, with the pinion 21 at the inner end of the screw-threaded portion of the shaft 7 and out of engagement with the fly wheel 1. To start the engine, power may be supplied to the motor through any suitable electrical means (not shown). The shaft 7 will be driven, through the reduction gear mechanism and the spring 10, in a clockwise direction, as viewed from the left in Fig. 1, at a rapidly increasing speed. Because of the inertia of the weighted pinion 21, the shaft 7 will rotate relatively to it and it will be actuated to the left into engagement with the fly wheel 1. As above stated, the impact of the pinion 21 will be absorbed by the buffer spring 23 which also causes the pinion to frictionally engage the screw-threaded shaft during the latter portion of its outward movement. The pinion 21 then rotates with the shaft 7 to crank the engine.

As the engine approaches each of its several compression points, an increased torque is necessary to rotate the engine shaft. Accordingly, the spring 10 will be contracted as the shafts 6 and 7 rotate relatively, the one to the other, and the spring will engage the split sleeve member 19. The tendency of the spring to further contract is then opposed by its frictional engagement with the sleeve and by the resilient force of the latter. Should the torque necessary to rotate the engine shaft be such that the spring is contracted to such degree that the sleeve engages the adjacent ends of the shafts 6 and 7, relative rotatable movement of these parts is further opposed by the frictional engagement between them and the sleeve.

As the engine recedes from the compression points, the frictional engagement of these parts is maintained for a material portion of the expansive movements of the spring and the sleeve. The sleeve operates, therefore, to damp out oscillations of the spring and the shafts 6 and 7 that are

caused by periodic variations in the torque required to rotate the engine shaft. Considerable torque is transmitted through the sleeve, thereby relieving the spring from a portion of its load which would otherwise be concentrated at the terminal loops. The latter constitute the weakest part of the spring. Disconnection of the pinion from the fly wheel during the movement of the engine from the compression points is prevented by the wedging action of the pinion and the screw-threaded shaft produced by the buffer-spring washer.

When the engine starts under its own power, the fly wheel 1 will rotate at a higher rate of speed than it was driven by the motor, and the pinion 21 will be caused to overrun the shaft 7. The pinion 21 will, therefore, be actuated to the right to its illustrated position, out of engagement with the fly wheel. If the engine becomes the driving member because of a failure to disconnect the pinion from the fly wheel, the spring 10 cannot be disconnected from the shafts 6 and 7. The end portion 14, which is a continuation of the loop portion 11, effectually prevents the inner end of the spring from being withdrawn through the recess 12 in the gear wheel 5.

At the other end of the spring, the loop portions 15 and 16 are so arranged that, when the motor is the driving member, the torque is transmitted through the loop portion 15 and the bolt 17, the loop portion 16 and the stud 18 preventing the opening of the loop portion 15 even though back-firing of the engine should occur. In case the bolt 17 should become loosened, or the loop portion 15 should become disconnected from it, the torque will be transmitted by the loop portion 16 and stud 18, and uncoiling of the loop 15 is prevented. When the fly wheel is the driving member, the torque is also transmitted by the loop portion 15 and the bolt 17. The end of the spring is securely anchored by means of the loop 16 and the stud 18. It will be obvious, therefore, that a movement of the end portion of the spring relatively to the bolt 7 and the stud 18, sufficient to effect its disconnection therefrom, is positively prevented.

Reference may now be had to Figs. 4 and 5, in which is illustrated a modification of my invention. A shaft 27, which is provided with a screw-threaded portion 28 and a buffer spring 23, is adapted to be driven through a mechanism comprising a friction clutch. The clutch mechanism comprises a gear wheel 29 that is mounted on the shaft 27 between two collar members 30 and 31 and is yieldingly connected thereto by means of disks 32 of any suitable friction material. The frictional engagement of these several parts is controlled by the angular position of the collar 31 relatively to a reduced screw-

threaded portion of the shaft 27. Movement of the collar 31, relative to the shaft 27, after these parts have been adjusted, is prevented by a locking device which may be, for example, a key 33, having radially extending arms which engage alined slots in the ends of the shaft 27 and the hub portion of the collar 31. The key is held in position by a suitable screw 34.

It will be noted that I provide a simple arrangement whereby oscillations of the several relatively rotatable parts are prevented during the operation of cranking the engine. The tendency of the pinion to become disconnected from the fly wheel when the engine recedes from its several compression points, is prevented by the provision of a buffer spring. The disconnection of the spring from the parts which it connects by the uncoiling of its end portions, is avoided by the use of the terminal loops arranged in accordance with my invention. These and other advantages will be apparent to those skilled in the art to which my invention appertains.

I claim as my invention:

1. In a starting mechanism, the combination with a motor-driven shaft, and a shaft in axial alinement therewith, of a spring for connecting said shafts, and a resilient member between said shafts and said spring.

2. In a starting mechanism, the combination with a motor-driven shaft, and a shaft in axial alinement therewith, of a spring for connecting said shafts, and a resilient sleeve member between said shafts and said spring.

3. In a starting mechanism, the combination with a motor-driven shaft, and a shaft in axial alinement therewith, of a helical spring for connecting said shafts, and a resilient cylindrical member between said shafts and said spring.

4. In a starting mechanism, the combination with a motor-driven shaft, and a screw-threaded shaft, of a gear wheel on one of said shafts having a recess, a spring for connecting said shafts, said spring having a loop portion projecting into said recess and an end portion extending substantially parallel to the plane of said gear wheel.

5. In a starting mechanism, the combination with a motor-driven shaft, and a screw-threaded shaft, of a spring for connecting said shafts, said spring having a terminal portion of substantially S-shape, and means connected to one of said shafts for engaging the loops of said terminal portion.

6. In a starting mechanism, the combination with a motor-driven shaft, and a screw-threaded shaft, of a spring for connecting said shafts, said spring comprising a plurality of loop portions at one end thereof, and means on one of said shafts for engaging said loop portions.

7. In a starting mechanism, the combina-

tion with a motor-driven shaft, and a shaft in axial alinement therewith, of a spring for connecting said shafts, and a member between said shafts and said spring for successively engaging the convolutions of said spring and said shafts.

8. In a starting mechanism, the combination with a motor-driven shaft, and a shaft in axial alinement therewith, of a spring

for connecting said shafts, and means for successively retarding contractile movement of said spring and relative movements of said shafts.

In testimony whereof, I have hereunto subscribed my name this 26th day of April, 1915.

LESTER M. TAYLOR.
